UNITED STATES PATENT OFFICE.

CHARLES H. BEELER, JR., OF PHILADELPHIA, PENNSYLVANIA, ASSIGNOR
TO MACKELLAR, SMITHS & JORDAN, OF SAME PLACE.

DESIGN FOR A FONT OF PRINTING-TYPE.

SPECIFICATION forming part of Design No. 13,474, dated December 12, 1882.

Application filed October 21, 1882. Term of patent 7 years.

To all whom it may concern:

Be it known that I, CHARLES H. BEELER, Jr., (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an ornamental letter shaded upon the right and bottom by a heavy line, the face of which is ornamented by a series of light lines extended very nearly across it and following the configuration or outline of the letter. Several of the

letters, as the B, D, E, F, H, I, K, L, P, R, T, and Y, have the up-and-down portion concaved upon the left, and the lower left-hand termination of the A, M, and N is triangular.

The character of the design is preserved in the lower-case and numerals, as clearly shown. In the lower-case the g, j, p, q, and y extend below the line.

Having now described my invention, I claim as new—

The design for a font of printing-type, substantially as shown and described.

C. H. BEELER, JR.

In presence of—

C. F. HUCH,
GEO. WM. WITHAM.
